[57] CLAIM

The ornamental design for a spreader for mayonnaise or the like, substantially as shown and described.

DESCRIPTION

FIG. 1 is a front elevational view of a spreader for mayonnaise or the like showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a cross-sectional view on an enlarged scale taken substantially along the line 6—6 in FIG. 1; and,

FIG. 7 is a cross-sectional view on an enlarged scale taken substantially along the line 7—7 in FIG. 1.

The rear elevational view is a mirror image of the front elevation shown.
